APPLICATION FILED MAY 7, 1907.

2 SHEETS—SHEET 2.

UNITED STATES PATENT OFFICE.

WILLIAM C. LUTHER, OF NEWARK, NEW JERSEY.

FOUNTAIN-PEN.

No. 863,803.

Specification of Letters Patent.

Patented Aug. 20, 1907.

Original application filed December 6, 1905, Serial No. 290,530. Divided and this application filed May 7, 1907. Serial No. 372,363.

To all whom it may concern:

Be it known that I, WILLIAM C. LUTHER, a citizen of the United States, residing at Newark, in the county of Essex and State of New Jersey, have invented certain new and useful Improvements in Fountain-Pens; and I do hereby declare the following to be a full, clear, and exact description of the invention, such as will enable others skilled in the art to which it appertains to make and use the same, reference being had to the accompanying drawings, and to letters of reference marked thereon, which form a part of this specification.

My present invention has reference, generally, to improvements in fountain pens, and the same is in the nature of a division of my former application for a patent for fountain pens, filed Dec. 6, 1905, Serial No. 290,530; and this invention has for its principal objects to provide a fountain pen, the holder and ink-containing reservoir of which is composed of a transparent or translucent material, so that the ink contained within the holder is always exposed to view, and the user of the pen can readily see when the reservoir or body of the pen has to be refilled with a fresh supply of ink.

A further object of this invention is to provide a novel and simply constructed suction or means which is movably connected with and forms a part of the pen, for refilling the interior of the reservoir or holder with a fresh supply of ink; and, furthermore, the device being of such a construction, to prevent the gathering of air back of the ink, as is often the case with the various constructions of fountain pens.

The object of following up the supply of ink, as it is being used up, by the plunger is, as has been stated, to prevent air from collecting back of the ink, and thus avoid the ink being forced by such collection of the air in too free a manner from the pen; but, another purpose of following up the ink as it is being exhausted by the plunger is to maintain also a substantially uniform and constant pressure back of the ink. It is also for this purpose that the body of the holder is made from a transparent material, that the various positions of the plunger, in following up the ink as it is being exhausted, may be readily regulated.

A further object is to so construct a fountain-pen that it can be used in the manner of a syringe for sucking a supply of ink into the holder; and, when removing that end-portion of the holder which carries the nib or writing pen, being capable of forcing any remaining ink from the interior of the holder, the plunger of the device by contact with the inner surface of the reservoir or holder, clearly removing all the ink from said surface, that a clean reservoir for a fresh supply of ink will be the result.

Other objects of this invention not at this time more particularly enumerated will be clearly understood from the following detailed description of the invention.

With these various objects of this invention in view, the said invention consists, primarily, in the novel fountain-pen; and, furthermore, this invention consists in the general arrangements and combination of devices, and certain novel features of construction of the various parts, all of which will be hereinafter more fully described and then finally embodied in the clauses of the claim which are appended to and which form an essential part of this specification.

The invention is clearly illustrated in the accompanying drawings, in which:—

Figure 1 is a plan view of a fountain-pen embodying the various features of my present invention. Fig. 2 is a view of the fountain-pen, the greater portion of the pen-holder being represented in longitudinal section, said view showing the suction-device in side elevation, within the closed holder, when the pen-holder has been filled with ink, and is ready for use in writing. Fig. 3 is a similar view of the same parts, showing the telescopically arranged parts of the suction-device in their extended relation and projecting from the upper end-portion of the pen-holder, prior to forcing the plunger of the device toward the nib or pen of the holder; and Fig. 4 is a similar view of the same parts, with the parts of the suction device still in their extended relation, but within the tubular holder, ready for sucking a fresh supply of ink into the holder. Fig. 5 is a longitudinal section taken on line 5—5 in Fig. 2, on an enlarged scale, of the upper end-portion of the pen-holder, and of the closed members of the suction device, the plunger, however, being shown in elevation; and Fig. 6 is a transverse section of the said parts said section being taken on line 6—6 in said Fig. 2. Figs. 7 and 8 are views similar to Figs. 4 and 2, respectively, showing the fountain-pen provided with a suction device of a modified construction, but still embodying the principles of this invention.

Similar characters of reference are employed in all of the said above described views, to indicate corresponding parts.

Referring now to the several figures of the drawings, the reference-character 1 indicates a hollow or tubular holder or barrel, which is preferably made from a transparent material, such as glass, celluloid, or the like, but which may be the usual hard rubber barrel, if desired. At its forward end the said tubular holder or barrel 1 is provided with the usual construction of ink-feeding member or sleeve 2 carrying the usual nib or pen 3, the said sleeve 2 being detachably connected with the said end of the holder or barrel in any usual and well-known manner. At its opposite end the said holder or barrel 1 is made with a reduced and shouldered end-portion 4, upon which is slipped and held by frictional contact, a second member or sleeve 5, the outer end of the said sleeve 5 being closed by means of a removable plug or cap 6, of substantially the con-

struction shown in the several figures of the drawings. While I prefer to have the said holder or barrel 1 of a transparent material, for the purposes hereinafter more fully specified, I prefer to make the sleeves or members 2 and 5 of a non-transparent material, preferably of vulcanized or hard rubber, whereby the general appearance of the fountain pen is greatly enhanced. The said plug or cap 6 is preferably provided with a reduced and shouldered end-portion 7 by means of which the said plug or cap is held in frictional, but removable engagement with the outer end-portion of the sleeve 5. While the said sleeve 5 is held in frictional engagement with the reduced and shouldered end-portion 4 of the holder or barrel 1, the said sleeve 5 may also be rotated upon said end-portion 4 for the purpose to be presently described.

Coming now to the construction of the suction-device for filling the said holder or barrel with ink, the said barrel or holder is provided with an internally arranged ring 10, which is suitably secured in its fixed position within the end of the holder or barrel, preferably by means of pins 11, as shown, or in any other suitable means. The said suction device comprises a plunger 12, which may be of rubber, cork, or any other flexible material, in slidable and frictional engagement with the inner cylindrical surface of said holder or barrel 1, said plunger 12 being disposed between a pair of compressor and re-inforcing disks or plates 13 and 14, which are suitably arranged upon the end-portion of a plunger-rod 15, and are suitably secured upon said rod and in their compressed relation upon the opposite faces of the plunger 12, by a nut 16 upon the screw-threaded end, (not shown) of the said plunger-rod 15. The said ring 10 acts as a stop, against which the disk or plate 13 is brought in contact, to prevent the withdrawal of the plunger 12 from the holder or barrel, when the telescopically arranged parts of the suction-device are drawn out or extended for operation, in the manner and for the purposes now to be more particularly set forth.

40 Encircling the said plunger-rod 15 is a sleeve 17, which is made with a pair of oppositely located spirally formed elongated slots or openings 18, extending from a point near one end of the sleeve 17 to a point near the other end of the said sleeve, the said spirally formed slots or openings 18, being made in the same manner as a double-threaded screw. The said rod 15 is provided at its free end 19 with a laterally extending pin 20, having its ends projecting from the opposite sides of the said rod, and respectively extending into the oppositely located slots or openings 18 of the sleeve 17. In this manner the said sleeve 17 is both slidably and rotatably arranged upon the plunger-rod, the end-portions of said pin 20 moving in said spiral openings or slots, until brought in engagement with the recessed end-portions 21 of said slots or openings 18. Encircling the said sleeve 17 is a second sleeve 22 which is made with a pair of oppositely located spirally formed elongated slots or openings 23, which extend from a point near one end of the sleeve 22 to a point near the other end of the sleeve, the said sleeve 17 being provided at its free end 24 with a laterally extending pin 25, having its ends projecting from the opposite sides of said sleeve 17, and respectively extending into the oppositely located slots or openings 23 of the sleeve 22. Thus, the said sleeve 22 is both slidably and rotatably arranged upon the sleeve 17,

end-portions of the pin 25 moving in said spiral openings or slots 23 until brought in engagement with the recessed end-portions 26 of the said slots or openings 23. Another sleeve 27, which encircles said sleeve 22, may be employed, said sleeve being made with a pair of oppositely located spirally formed elongated slots or openings 28, which extend from a point near one end of the sleeve 27 to a point near the opposite end of the sleeve, the said sleeve 22 being provided at its free end 29 with a laterally extending pin 30, having its ends projecting from the opposite sides of said sleeve 22, and respectively extending into the oppositely located slots or openings 28 of the sleeve 27. In this manner, the said sleeve 27 is both slidably and rotatably arranged upon the sleeve 22, the end-portions of the pin 30 moving in said spiral openings or slots 28 until brought in engagement with the recessed end-portions 31 of said slots or openings 28.

From an inspection of the several figures of the drawings, it will be seen, that these various sleeves can be closed up, in the manner of the sections of a telescope, upon the said plunger-rod 15, so as to be directly within the sleeve 5, and out of sight, when not in use, as indicated in Figs. 2 and 5. That the said telescopically arranged sleeves may be drawn out into their extended relation shown in Fig. 3 of the drawings, the said sleeve 27, as will be seen more particularly from an inspection of Fig. 5, has arranged and suitably secured within its free end-portion 32, a disk or plate 34 which is provided with a stud or stem 33, extending into and loosely arranged in a tubular portion 35 of the previously mentioned cap or plug 6. The said stud or stem 33 is provided with a screw-threaded socket 36 into which is screwed a screw 37, having its head 38 in retaining engagement with a washer 39 resting in a depression 40 in the face of said cap or plug 6, substantially as shown. In this manner, the parts are operatively connected, and the said cap or plug 6 serves as a finger-piece or knob, for bringing the telescopically arranged sleeves and the plunger and its rod from the relation indicated in Fig. 2 to their extended positions shown in Fig. 3, until the various pins are brought into holding engagement with the several recessed parts 21, 26 and 31 of the respective sleeves 17, 22 and 27. The parts are now in position for moving the plunger 12 in a reciprocatory manner within the holder or barrel 1, as in a syringe or pump, from the position in said Fig. 3 to that represented in Fig. 4 of the drawings. By dipping the nib or pen into the ink, and returning the plunger and its parts, once more to their positions shown in said Fig. 3, the ink is readily sucked into the holder or barrel 1, the latter thereby becoming replenished with a complete supply of ink. By means of a slight twist, the various pins can again be removed from their retaining engagement with the recessed portions 21, 26 and 31 of the respective slots or openings 18, 23 and 28 of the sleeves 17, 22 and 27, and by pressing the parts in the direction toward the opposite end of the holder or barrel 1, the said parts of the suction device are again returned into their closed relation within the sleeve 5, with the cap or plug 6 once more closed down upon the end of said sleeve 5, as shown.

Of course it will be understood, that although in the foregoing description and in the drawings I have described and illustrated an arrangement of three tele-

- scopically arranged sleeves 17, 22 and 27, the number of such sleeves and their arrangement may be departed from, and a smaller or larger number of such sleeves may be used, if desired. Instead of the spirally arranged slots or openings in the various sleeves, the said tubes or sleeves 17, 22 and 27 may be provided with the straight and longitudinally extending slots or openings 41, 42 and 43, and the retaining off-sets or recessed parts 44, 45 and 46, respectively, and as clearly indicated in 5 Figs. 7 and 8 of the drawings, the actions of the several parts being the same as hereinabove described, in connection with the construction shown in said Figs. 1 to 6 inclusive, except that the sleeves instead of having a rotary motion in addition to the longitudinal motion, 10 are capable only of a reciprocatory sliding motion longitudinally one upon the other. After the holder or barrel has been replenished with ink, and the parts of the suction device have been closed, in the manner shown in 15 said Figs. 2, 5 and 7, the pen can be used for writing.
- 20 I claim:—
1. In a fountain-pen, a tubular holder adapted to receive and contain ink, and a suction device in said holder comprising a plunger, a rod connected with said plunger, and telescopically arranged sleeves provided with spirally formed slots, and pins on said rod and some of said sleeves, the end-portions of said pins extending into the said slots of the respective sleeves, all arranged that said sleeves may be extended for the manipulation of said plunger, a stud or stem on one of said sleeves, and a plug on said stud or stem, said plug serving as a closure to the end of said holder and as a fingerpiece for the said suction-device, substantially as and for the purposes set forth. 25
  2. In a fountain pen, a tubular holder adapted to receive and contain ink, said holder being made from a transparent material, and having non-transparent end-sleeves, and a suction-device in said holder and normally hidden from view by being contained in one of said non-transparent sleeves, substantially as and for the purposes set forth. 30
  3. In a fountain pen, a tubular holder adapted to receive and contain ink, said holder being made from a transparent material, and having non-transparent end-sleeves, and a suction-device in said holder and normally hidden from view by being contained in one of said non-transparent sleeves, said suction-device comprising a plunger, a rod connected with said plunger, and telescopically arranged sections for the manipulation of said plunger, substantially as and for the purposes set forth. 35
  4. In a fountain pen, a tubular holder adapted to receive and contain ink, said holder being made from a transparent material, and having non-transparent end-sleeves, and a suction-device in said holder and normally hidden from view by being contained in one of said non-transparent sleeves, said suction-device comprising a plunger, a rod connected with said plunger, and telescopically arranged sleeves provided with spirally formed slots, and pins on said rod on some of said sleeves, the end-portions of said 40
  5. In a fountain pen, a tubular holder adapted to receive and contain ink, said holder being made from a transparent material, and having non-transparent end-sleeves, and a suction-device in said holder and normally hidden from view by being contained in one of said non-transparent sleeves, said suction-device comprising a plunger, a rod connected with said plunger, and telescopically arranged sleeves provided with spirally formed slots, and pins on said rod and some of said sleeves, the end-portions of said pins extending into the said slots of the respective sleeves, and all arranged that said sleeves may be extended for the manipulation of said plunger, substantially as and for the purposes set forth. 45
  6. A fountain pen comprising a tubular holder adapted to receive and contain ink, a sleeve at one end of said holder, a plug detachably connected with an end of said sleeve, and a suction device operatively connected with said plug, said suction device comprising a plunger, a rod connected with said plunger, and telescopically arranged sleeves arranged between said rod and plug, said sleeves being provided with spirally formed slots, and pins on said rod and some of said sleeves, the end-portions of said pin extending into the said slots of the respective sleeves, and all arranged that the said sleeves may be extended for the manipulation of said plunger, substantially as and for the purposes set forth. 50
  7. In a fountain pen, the combination, with a tubular holder or barrel, of a suction device, comprising a plunger movably arranged in said holder or barrel, and a series of telescopically arranged sleeves connected with said plunger for producing a reciprocatory movement of said plunger, each sleeve being provided with spirally formed slots, and each slot being formed with a pin-retaining recess, and pins having their end-portions extending into and movably arranged in the respective slots, substantially as and for the purposes set forth. 55
  8. In a fountain pen, the combination, with a tubular holder or barrel, of a suction device, comprising a plunger movably arranged in said holder or barrel, and a series of telescopically arranged sleeves connected with said plunger, each sleeve being provided with spirally formed slots, and each slot being formed also with a pin-retaining recess, pins having their end-portions extending into and movably arranged in the respective slots, and a ring within said holder or barrel, said ring serving as a stop against which said plunger is moved, substantially as and for the purposes set forth. 60
- In testimony, that I claim the invention set forth above I have hereunto set my hand this 2nd day of May, 1907.
